WASHING MACHINE

Kenton D. McMahan, Scotia, N. Y., assignor to
 General Electric Company, a corporation of
 New York

Application June 29, 1940, Serial No. 343,217

12 Claims. (Cl. 68—38)

The present invention relates to washing machines having an oscillatory or reciprocatory agitating element for agitating the liquid and clothes.

The object of my invention is to provide an improved construction in washing machines of this type, and for a consideration of what I believe novel and my invention attention is directed to the following description and the claims appended thereto.

In the accompanying drawings, Fig. 1 is a sectional elevation of a washing machine embodying my invention; Fig. 2 is a top plan view of the washing machine; Fig. 3 is a sectional view taken on line 3—3 of Fig. 2; Fig. 4 is a sectional elevation of a modification; Fig. 5 is a top plan view of the agitator of the modification; Fig. 6 is a sectional view taken on line 6—6 of Fig. 5; Fig. 7 is a sectional elevation of another modification in which the agitating element is reciprocated vertically; Fig. 8 is a sectional view taken on line 8—8 of Fig. 7; and Fig. 9 is a diagrammatic view of the driving mechanism.

Referring to the drawings, there is shown a washing machine having a tub 1 supported at its outer edge on a rubber bead 2 on the upper edge of a skirt 3 to which are fixed supporting legs 4. Fixed to the skirt 3 is a gear casing 5 having an agitator post 6 projecting upward through a central opening in the bottom of the tub 1 and having a wringer post 7 extending upward along the outside of the tub. Suitable mechanism is provided in the gear casing for oscillating an agitator shaft 8 and for rotating a wringer drive shaft (not shown) extending through the wringer post 7. Such mechanism is well known, and an illustration is not required. The bottom of the tub is clamped between a flange 9 on the agitator post and a nut 10 threaded on the agitator post, suitable gaskets 11 being arranged on either side of the bottom wall of the tube to prevent leakage.

The agitator shaft 8 is journaled in a bearing 12 in the upper end of the agitator post 6. The upper end of the agitator shaft 8 projects above the agitator post and has fixed thereto a drive nut 13 fitting within a socket 14 in the upper end of an agitator sleeve 15. The agitator sleeve depends around the agitator post 6 and has fixed in its lower end a guide sleeve 16 journaled on a bearing 17 fixed to the agitator post. At the lower end of the sleeve 15 is fixed a disk 18 spaced above the bottom of the tub. The disk 18 comprises an annular imperforate portion 19 adjacent the sleeve 15 and outer segmental perforated sections 20. The perforations comprise the

greater part of the area of the segmental sections. The outer edges of the sections 20 are provided with downwardly extending flanges 21 adjacent the side walls of the tub. The radial edges of the segmental sections 20 are beaded as indicated at 22, and adjacent edges are spaced apart to provide radial slots 23. Fixed to the under side of the disk 18 are a depending circular vane 24 at the outer edge of the imperforate annular portion 19 and arcuate vanes 25 depending from the segmental sections 20 intermediate the vane 24 and the flanges 21. The vanes or baffles 25 are for the purpose of preventing radially outward flow of liquid beneath the disk 18 during oscillation of the agitator. Midway between the edges of the radial slots 23 are radial vanes 26 having walls 27 flaring downward and outward from the apexes of the vanes toward the bottom of the tub. The inner ends of the walls 27 are fixed to the baffle 24. The outer ends of the walls 27 are fixed to the flanges 21. Midway between the ends, the walls 27 are secured to the baffles 25. The apexes of the vanes 26 are substantially midway between the edges of the slots 23 and provide passages 28 and 29 on opposite sides thereof. These passages have an area which is substantially smaller than the area of the perforations in the adjacent segmental sections 20. The liquid flowing through the passages 28 or 29 accordingly has a higher velocity than the liquid flowing through the perforations.

When the agitator is being oscillated in the direction of the arrow 30 of Fig. 3, a high velocity jet of liquid is forced outward in the direction of the arrows 31 through the passage 28 between the leading or front face of the vane 26 as regards the direction of movement of the agitator and the adjacent edge of the slot. To take the place of the liquid discharged in this jet, liquid is drawn downward through the perforations 32 in front of the vane 26 as regards the direction of rotation, as indicated by the arrows 33. This liquid produces a suction drawing the clothes against the segmental section in front of the vane 26 as regards the direction of movement of the agitator. The jet discharged through the passage 28 has an injector action on the passage 29 between the trailing face of the vane 26 and the adjacent edge of the slot, which passage is behind the vane 26 as regards the direction of movement of the agitator. The passages 28 and 29 are so related that this injector action produces a suction in the passage 29 preventing inward movement of the liquid. In Fig. 3 only one of the vanes 26 is illustrated. The vane to the left of the vane illustrated would pro-

duce a suction through the perforations 34, causing a flow of liquid indicated by the arrows 35. This suction would likewise tend to produce an inward flow through the passage 29, which flow is, however, blocked by the injector action of the jet discharged through the passage 28. The injector action results from the fact that the passages 28 and 29 intersect in that a jet flowing through one of the passages flows over the other passage. When the direction of movement of the agitator is reversed, a jet is discharged outwardly through the passage 29 which is now in front of the vane as regards the direction of movement of the agitator, and the injector action of this jet prevents inward flow from the passage 28 which is now behind the vane 26 as regards the direction of movement of the agitator. The flow through the perforations is, however, always inward, regardless of the direction of movement of the agitator.

During the oscillation of the agitator, clothes are accordingly always sucked down against the perforated sections 20 and, while held by suction against these surfaces, are subjected to a scrubbing action due to the forcible oscillation or reciprocation of the agitator relative to the liquid in the tub. At the slots 23 and in front of the vanes 26 as regards the direction of movement of the agitator, are upwardly directed jets of liquid which are directed tangentially over the perforated section behind the vanes 26 and tend to remove the clothes therefrom. The jets also produce a circulation of the clothes in vertical planes perpendicular to the length of the slots 23. This circulation produces a turnover of the clothes so that all parts thereof are brought into contact with the perforated reciprocating rubbing surfaces 20.

In Figs. 4 to 6 is shown a modified form of agitator used in a machine of the previously described construction, corresponding parts being indicated by the same reference numerals. The agitator comprises a tubular portion 36 in the upper end of which is fixed a casting 37 having a socket therein receiving the drive nut 13 on the upper end of the agitator shaft 8. The tubular portion 36 depends around the agitator post 6 flaring downward and outward toward the bottom of the tub to provide a frusto-conical portion 38 which terminates adjacent the bottom of the tub in a downwardly extending flange 39. Within the frusto-conical portion 38 are arcuate flanges 40 carrying at their lower ends a sleeve bearing 41 journaled at 42 on the agitator post 6. Depending from the under side of the frusto-conical portion 38 are integral ears 43 to which is secured a disk 44 closing the bottom of the agitator. Integral with the upper side of the disk 44 is a circular rib 45 which, like the flange 25 of the previously described construction, prevents radially outward movement of the liquid in the space between the disk and the lower side of the frusto-conical portion 38. The disk is provided with an opening 46 loosely surrounding the agitator post. Around the edges of the opening 46 the disk is in contact with the bearing 42 and with the lower edges of the flanges 40. As shown in Fig. 5, the frusto-conical portion 38 is provided with three segmental sections 47 each of which is provided with a series of parallel ribs 48 extending inward from the outer periphery and between which are parallel rows of perforations 49. Between the segmental sections 47 are radial slots 50 the sides of which are bounded by adjacent edges of the segmental sections and

the outer and inner ends of which are bounded respectively by the ears 43 and by flanges 51 integral with and depending from adjacent ends of the flanges 40. The slots 50 occupy only the outer portion of the agitator. If the length of the slots is decreased so the slots occupy only the extreme outer portion of the agitator, the rib 45 may be omitted since there will then be substantially no tendency for radial outward flow in the slots 50. Intermediate the sides of the slots 50 are radial vanes 52 having sides 53 integral with the disk 44. The upper ends of the vanes 52 project slightly above the slots 50 and provide passages 54 and 55 on each side of the vanes.

The operation of the agitator is much like that of the previously described construction. When the agitator is moving in the direction of the arrow 56, jets of liquid are discharged in the direction indicated by the arrow 57 through the passages 54 in front of the vanes as regards the direction of movement of the agitator. At the same time there is an inward flow of liquid through the perforations 58 in front of the vanes 52 as regards the direction of movement of the agitator and also an inward movement of liquid through the perforations 59 behind the vanes 52 as regards the direction of movement of the agitator. The jet discharged through the passage 54 has an injector action which prevents inward flow through the passage 55. When the direction of movement of the agitator is reversed, an outward jet is discharged through the passage 55 and liquid continues to flow inward through the perforations 58 and 59. Since liquid always moves inward through the perforations, the clothes are drawn against the perforations and subjected to a scrubbing action by the ribs 48 and the edges of the perforations. Since the agitator is positively oscillated, there will be some slippage between the clothes and the perforated sections of the agitator and some of the clothes will move over the slots 52. These clothes will come under the influence of the jets discharged upwardly through the slots and will be lifted off the perforated sections of the agitator and moved upward by the liquid currents. The jets discharged through the slots 50 accordingly have the dual function of producing a circulation of the clothes within the tub and of moving the clothes out of contact with the perforated sections of the agitator so that other clothes can be brought against the perforated sections and subjected to a scrubbing action. The frusto-conical portions 38 of the agitator have a steeply tapered portion 60 adjacent the agitator shaft. This steeply tapered portion causes the clothes to slide toward the outer edges of the agitator and prevents tangling of the clothes at the center of the tub. The jets discharged upwardly through the slots 50 have a velocity increasing with the distance from the center of the agitator. There is accordingly a generally upward circulation along the side walls of the tub and a downward circulation at the center of the tub. This circulation will be accentuated if the slots 50 are only in the extreme outer part of the agitator. The circulation produced by the agitator is therefore of two kinds: a circulation about radial axes due to the jets discharged through the slots 50 and a circulation in radial planes around the agitator due to the greater upward flow and higher velocity of the jets at the outer part of the slots 50.

In Figs. 7 to 9 is shown a modified form of agitator which is reciprocated vertically by means

of a shaft 61 extending up through the agitator post 6 of the previously described machine. As shown diagrammatically in Fig. 9, the shaft 61 reciprocated by an eccentric 62 rotated by a driving shaft 63 and fitting in a cross head 64 integral with the shaft 61. The agitator, which is fixed to the upper end of the shaft 61 in a manner not shown, comprises outer perforate cylindrical sections 65 and 66 and an inner imperforate cylindrical section 67. As shown in Figs. 7 and 8, the inner and outer cylindrical sections are secured together by radial ribs 68. The upper end of the agitator is closed by a disk 69. The lower end of the agitator is closed by an annular ring 70 fixed between the lower ends of the cylindrical sections 65 and 67 and by an annular ring 71 fixed to the inside of the cylindrical section 67 and terminating at its inner edge in a flange 72 slidable on a sleeve 73 fixed to the agitator post 6. The adjacent ends of the perforated cylindrical sections 65 and 66 are spaced apart to provide a slot 74 surrounding the central part of the agitator. Midway between the edges of this slot is a vane 75 internal with the inner cylindrical section 67. The vane has arcuate side walls 76 which merge into the vertical walls of the cylindrical section 67. The adjacent ends of the perforated sections 65 and 66 are provided with correspondingly curved portions 77.

In use, the agitator is reciprocated vertically at a high speed and through a short stroke by the vertical shaft 61. When the agitator is moved upward, a jet of fluid is discharged radially through the passage between the upper side of the vane 75 and the lower end of the cylindrical section 66 in the direction indicated by the arrow 78. As in the previously described constructions, this jet blocks or prevents inward flow of liquid through the passage on the lower side of the vane 75. During downward movement of the agitator, a jet is discharged through the passage between the lower side of the vane 75 and the upper end of the cylindrical section 65 in the direction indicated by the arrow 79. This jet blocks the passage on the upper side of the vane 75. During both the upward and downward movement of the agitator, fluid is drawn inward through the perforations in the sections 65 and 66 to replace the fluid discharged outwardly through the intersecting passages through the slot 74 on each side of the vane 75. The net result is that clothes are drawn inward at the top and the bottom of the tub against the rapidly reciprocating perforated sections and are forced outward at the center of the tub by radial jets. Due to the high speed of reciprocation of the agitator relative to the liquid, there will be some slippage between the clothes and the perforated sections which results in a rubbing or scrubbing action on the clothes. Upon reaching the slot 74 the clothes will be forcibly removed from the perforated sections by the high speed jets continually discharged through the slot. During operation, the agitator causes considerable turbulence in the washing liquid. However, since liquid is continually being discharged in a radial direction from the center of the agitator and at the same time is being drawn radially inward toward the agitator at the top and at the bottom of the tub, there is a circulation or turnover of the clothes in radial planes surrounding the agitator in the general direction indicated by the arrows 80 and 81.

In all of the constructions there is a hollow agitator having a rapidly reciprocated rubbing

surface presented toward the clothes, there being in said surface perforations through which liquid flows inwardly into the interior of the agitator and a slot through which high speed jets are discharged outwardly from the interior of the agitator. The area through which the inward flow takes place is greater than the area of the slot. In all forms of the invention the clothes are drawn against the rubbing surface by the inward flow of liquid and are there subjected to a rubbing or scrubbing action. The clothes are removed from the rubbing surface by the outwardly flowing jets which may have the additional function of causing circulation of the clothes within the tub so all parts of the clothes will be in turn brought under the action of the agitator.

What I claim as new and desire to secure by Letters Patent of the United States, is:

1. In a washing machine, a liquid receiving tub, a submerged reciprocatory agitator therein having a rubbing surface presented to the clothes, means for reciprocating said surface relative to the liquid in the tub, a slot in said surface transverse to the direction of movement of said surface, a vane on the agitator intermediate the edges of the slot and inward of said surface, the leading and trailing faces of the vane defining with the adjacent edges of the slot passages respectively in front of and behind the vane as regards the direction of movement of the vane, said leading face of the vane directing a stream of liquid from the passage in front of the vane over said rubbing surface and transverse to the passage behind the vane as regards the direction of movement of the vane, openings through said rubbing surface, and passages inward of the rubbing surface leading from said openings to said passages in front of and behind said vane.
2. In a washing machine, a liquid receiving tub, an agitator therein having a submerged reciprocatory rubbing surface presented toward the clothes, a slot in said surface transverse to the direction of reciprocation, openings in said surface on each side of said slot, and a vane beneath said surface intermediate the edges of said slot and defining therewith passages respectively in front of and behind the vane as regards the direction of movement of the agitator, said vane serving to discharge a jet of liquid outward through the passage in front of the vane as regards the direction of movement of the agitator, said jet being discharged across the other passage and having an injector action thereon preventing inward flow through said other passage.
3. In a washing machine, a liquid receiving tub, an agitator therein having a submerged reciprocatory rubbing surface, a slot in said surface transverse to the direction of reciprocation, openings in said surface on each side of said slot, a vane beneath said surface intermediate the edges of the slot and defining therewith passages respectively in front of and behind the vane as regards the direction of movement of the agitator through which liquid is unidirectionally discharged during reciprocation of the agitator whereby liquid is drawn in through said openings.
4. In a washing machine, a liquid receiving tub, an agitator oscillatable on a vertical axis and having a disk adjacent the bottom of the tub, means providing a space beneath said disk substantially closed at the bottom and at the outer edges, a radial slot in said disk, and perforations in said disk intermediate said slots.
5. In a washing machine, a liquid receiving

tub, an agitator oscillatable on a vertical axis and having a disk adjacent the bottom of the tub, means providing a space beneath said disk substantially closed at the bottom and at the outer edges, a radial slot in said disk, perforations in said disk on each side of said slot, a radial vane in said space and intermediate the edges of said slot, said vane cooperating with the edges of the slots to define passages respectively in front of and behind the vanes as regards the direction of movement of the disk, the passages in front of the vanes serving to direct liquid over the passages behind the vanes, and means for oscillating the agitator.

6. In a washing machine, a liquid receiving tub, an agitator oscillatable on a vertical axis and having a disk adjacent the bottom of the tub, means providing a space beneath said disk substantially closed at the bottom and at the outer edges, a radial slot in said disk, perforations in said disk on each side of said slot, a radial vane in said space beneath the slots, defining with the edges of the slot passages through which liquid is unidirectionally discharged during oscillation of the agitator and means for oscillating the agitator.

7. In a washing machine, a liquid receiving tub, an oscillatory agitator having a hollow body flaring downward and outward toward the bottom of the tub, a radial slot at the outer part of said body, perforations on the inner and outer parts of said body, and a vane within said body intermediate the edges of said slot.

8. In a washing machine, a liquid receiving tub, an oscillatory agitator having a disk adjacent the bottom of the tub, a radial slot in said disk, walls defining with said disk radially spaced zones beneath said disk closed at the top and bottom and at the inner and outer edges, openings in said disk intermediate said slots, and a vane beneath the disk intermediate the edges of the slot.

9. In a washing machine, a liquid receiving tub, a vertically reciprocable hollow agitator, a horizontal slot in the outer surface of the agitator, perforations in the agitator above and below the slot, and a vane within the agitator intermediate the edges of the slot.

10. In a washing machine, a liquid receiving tub, a vertically reciprocable hollow agitator, a discharge opening from the interior of the agitator intermediate the upper and lower ends, intake openings to the interior of the agitator above and below said discharge opening, means within the agitator for drawing liquid unidirectionally in through said intake openings and for discharging liquid unidirectionally out through said discharge opening, and means for reciprocating said agitator.

11. In a washing machine, a liquid receiving tub, a vertically reciprocable agitator comprising vertical inner and outer cylindrical parts, said outer cylindrical parts being perforated and providing a horizontal slot intermediate the upper and lower ends of the agitator communicating with the space between the inner and outer cylindrical parts, and a vane in the space between the inner and outer cylindrical parts cooperating with the edges of the slot to provide intersecting passages.

12. In a washing machine, a liquid receiving tub, an agitator therein having a submerged perforated reciprocating rubbing surface presented to the clothes, means for reciprocating said surface relative to the liquid in the tub, means for drawing liquid continuously inward through said surface whereby the clothes are drawn against the surface and for forcing jets of liquid across said surface tending to remove the clothes from said surface.

KENTON D. McMAHAN.
